UNITED STATES PATENT OFFICE.

WILLIAM A. SMITH, OF NIAGARA FALLS, NEW YORK.

DESIGN FOR A FAN.

Specification forming part of Design No. 7,017, dated December 2, 1873; application filed September 6, 1873.
[Term of Patent 3½ years.]

To all whom it may concern:

Be it known that I, WILLIAM A. SMITH, of Niagara Falls, in the county of Niagara and State of New York, have invented a Design for Fans, of which the following is a specification:

The nature of my design is fully represented in the accompanying drawings, to which reference is made.

Figure 1, *a a a a* represent the body of the fan; B B, the outer lines from the right and left points toward a common point at the ex-

treme outer end or top of the fan; C C, the lines of shape from the right and left points toward the handle. D D is an opening of the form shown.

What I claim as my invention is—

The design for a fan, substantially as described and shown.

WILLIAM A. SMITH.
